UNITED STATES PATENT OFFICE.

CHARLES CAREY MANKER, OF PITTSBURGH, PENNSYLVANIA, ASSIGNOR TO MORLEY-MANKER COMPANY, INCORPORATED.

VAPORIZER FOR HEAVY OILS.

1,343,635.

Specification of Letters Patent. Patented June 15, 1920.

Application filed March 19, 1918. Serial No. 223,307.

To all whom it may concern:

Be it known that I, CHARLES C. MANKER, a citizen of the United States, and a resident of Pittsburgh, in the county of Allegheny and State of Pennsylvania, have invented certain new and useful Improvements in Vaporizers for Heavy Oils, of which the following is a specification.

My invention relates to improvements in vaporizers for heavy oils such as kerosene and the like, for use in connection with automobile engines or gas engines in general.

An object of my invention is to provide a comparatively simple device by means of which the engine may be started on the low grade oils, thereby obviating the necessity of carrying additional fuel, such as gasoline, for starting purposes.

A further object of my invention is to provide a device which will vaporize heavy oils and which dispenses with the ordinary carbureter.

A further object of my invention is to provide a vaporizing device in which the heavy oil is heated to the vaporizing temperature, this temperature being maintained uniform through the action of a thermostat.

A further object of my invention is to provide a device of the character described in which the starting of the engine is accomplished by an auxiliary heating device which vaporizes sufficient oil to cause the engine to operate and which automatically eliminates the auxiliary heating means after the starting of the engine and continues the vaporization by means of heat supplied from the exhaust gases from the engine.

A further object of my invention is to provide a device of the type described made up in units which are interchangeable so that a vaporizer of greater or less capacity may be installed readily, depending upon the size and power of the engine which is used in connection therewith.

Other objects and advantages will appear in the following specification and the novel features of the invention will be particularly pointed out in the appended claims.

My invention is illustrated in the accompanying drawings forming part of this application, in which:

Figure 1 is a central vertical section through the device,

Fig. 2 is a side elevation of the device, and

Fig. 3 is a section on the line 3—3 of Fig. 1.

In carrying out my invention I provide a series of castings of circular form, these castings being shown at 1. Each of these castings is provided with a series of vertically extending passageways 2 provided by tubes 3 which extend through the interior chamber 4 of the castings so that air or gas going through the passageways 2 may be heated by hot products of combustion in the heating chamber 4 as hereinafter described.

Each of the castings 1 has an upper flange 5 and a lower flange 6 set inwardly from the outer wall of the casting so as to provide means for fitting thereto casing sections such as those shown at 7. There may be as many of these casing sections and castings 1 as desired, the number depending upon the size and capacity of the engine with which the device is used. The uppermost casting 1 is provided with a top 8 having an air opening 9 therein. The lowermost casting is connected with a conical shaped casing portion 10 and below the casing portion 10 and secured thereto, is a fuel float chamber 11. The latter is provided with a float 12 which is pivotally mounted at 13 and which is connected with an inlet valve 14. The latter is designed to govern the inflow of the fuel oil through the pipe 15 which is designed to be connected to a suitable source of supply, not shown. The valve 14 is provided with a guide stem 16 extending into an opening in a plug 17 carried by the valve casing 18. A screw cap 19 is provided for permitting access to the valve from above.

Near the bottom of the float chamber 11 is a draining tube 20 which is normally closed by means of a plug 21. Extending upwardly through the float chamber and preferably made integral therewith is a tube 22 having openings 23 near the bottom thereof. A plug 24 is screwed into the bottom of the tube 22, this plug being provided with insulating bushings 25 for the circuit wires 26 which lead to a filament 27 disposed in the interior of the tubes 22 and preferably above the openings 23.

The top of the float chamber is covered

by a plate 28 which is in fact the bottom portion of the casing section 10. Just above the plate is a series of openings which extend through the casing portion 10 and which communicate with the outer atmosphere as shown in Fig. 2. The upper end of the tube 22 projects through the plate 28 and is provided with a wire gauze 30 of proper mesh which serves to act as a fire 5 check and also prevents fuel from splashing out of the tube as will be explained later. A cylindrical sleeve 31 fits over the upper end of the tube 22, the lower end of the sleeve resting on the plate 28. The sleeve 10 has perforations 32 in its walls. A conical shield or partition 33 extends downwardly from the top of the sleeve 31 and outwardly to the side walls of the casing 10. This partition is provided with perforations 15 34 20 whose purpose will be explained later.

The lowermost casing portion 10 has a valve casing 35 secured to it. A valve 36 has its seat in this casing and the valve stem 37 is continued upwardly and is connected with a thermostat 38 disposed in a casing 39. The thermostat is provided with regulating means consisting of a threaded stem 40 and this stem may be locked in position by a jam nut 41.

30 On the opposite side of the casting which bears the thermostat casing 39, is a U-shaped pipe 42 having therein a butterfly valve 43. The upper end of the said pipe is provided with a wire gauze 44 and near the lower 35 end of the pipe is an atomizer 45 which communicates by means of a tube 46 with the lower part of the float chamber 11, the latter having a tube 47 extending therefrom by means of which the connection to 40 the pipe 46 is made.

Referring again to Fig. 1, I have shown therein a Y-tube 48, one branch of which communicates with the chamber 4 of the uppermost casting 1, the other branch communicating with the chamber 4 of the next lower casting. On the opposite side of the device is a similar Y-tube 49 having communication with the two upper castings as clearly shown in the drawing.

50 From the foregoing description of the various parts of the device, the operation thereof may be readily understood.

The casing 39 of the thermostat is connected with the intake manifold of the engine, not shown, the Y-tube 49 is connected with the muffler and the Y-tube 48 is connected to the exhaust manifold. Let us assume that there is a heavy oil like kerosene in the float chamber 11. Current from any 55 suitable source, as from a battery, not shown, is passed through the filament 27 which is submerged in the oil in the tube 22, the oil entering the tube as heretofore explained, through the openings 23. The filament does 60 65 not become incandescent on account of the

rapid radiation of heat into the liquid but rapidly raises the temperature of the oil to the point of vaporization. This vapor passes upwardly through the gauze and into the tube or sleeve 31, where it meets air 70 through the perforations 32, which are supplied by the air intakes 29, and as will be explained later, by air entering the perforations 34. The mixture of the air and vapor forms the initial fuel charge and this is 75 ignited by means of a spark plug 50 connected with any suitable source of current. This source is preferably that which operates the automatic starting device, such as those supplied with modern automobiles. 80 The spark continues while the engine is being turned over with the starter. The battery current to the filament 27 is cut out after the engine is started by any suitable means, such as an automatic switch, not 85 shown. Owing to the suction created by the cylinders of the engine, the products of combustion from the ignited charge at the top of the sleeve 31 pass upwardly through the flues or passageways 2 of the lowermost 90 casting and into the chamber 51 formed by the section 7 of the casing. From thence they are drawn through the tubes 42, through the heating chamber 4 of the castings and past the thermostat 38 and on into 95 the engine. The suction of the engine also causes oil to pass up the tubes 46 and through the atomizer 45 into the tube 42 where it meets the hot products of combustion, these products being additionally heated by passing through the chambers 4 around the hot tubes 3.

Now the thermostat 38 has been previously set so as to operate when a certain temperature is reached to open the valve 36 so as to 10 admit air to the passageways or flues 2. This cold air mixes with the heated products and is carried around with them in the manner described. It tends to perform two functions, first, to prevent too high a 11 temperature and second, to furnish the necessary air for the vaporized fuel coming through the atomizer 45. As soon as the engine starts on the charge thus furnished, the exhaust gases pass through the chambers 11 4 of the two upper castings and heat the tubes 3. Air is drawn through the openings 9 at the top of the device and passes through the tube, thence into the chamber 51 and mixes with the air and gas which is being 12 drawn through the pipe 42 and subsequently through the chamber 4 of the lower casting by the suction of the engine. In a very short time this heated air is sufficient to supply all of the necessary heat for vaporizing 12 the fuel. The thermostat will not permit the device to be overheated because, as stated before, when the temperature has exceeded a predetermined point, the valve 36 is opened wider and more cold air is admitted. 13

It is intended that the thermostat will maintain the uniform temperature of the mixture of air and atomized oil which enters the chamber 4 of the lower casting from the 5 tube 42, so that the vaporization of the oil will be at a constant temperature irrespective of atmospheric conditions.

As stated before, the battery current is cut off after the engine is started by any 10 suitable means. When this current ceases to flow through the filament 27, the temperature of the liquid contained in the tube 22 immediately falls off so that vapor ceases to pass out of the upper end. This extinguishes the flame so that thereafter, the 15 fuel is supplied through the pipe 46 and the atomizer 45.

It will be seen that I have provided a device by means of which the engine may be 20 started on a heavy oil. This obviates the necessity of using a lighter, more volatile fuel and also obviates the necessity of providing an additional carburetor for said lighter fuel. I have shown two castings as 25 being connected with the exhaust manifold at one end and the muffler with the other but obviously, with a large engine, additional sections might be provided in accordance with the capacity of the engine. The device 30 is of such a size that it can be readily installed under the hood of an automobile, or in any other convenient place.

I claim:-

1. A vaporizing device for heavy oils, 35 comprising an oil chamber, a burner communicating therewith, means within the burner for initially heating a portion of the heavy oil to the vaporizing temperature, means for mixing air with said vaporized oil, means for initially igniting the mixture, an atomizer for atomizing a portion of said heavy oil, means for mixing air with the atomized oil, and means for heating the last named mixture by the heat of the initially 45 ignited charge.

2. A vaporizing device for heavy oils comprising a casing, an oil chamber carried by the casing, means for initially heating a portion of the oil to the vaporizing temperature, 50 means for mixing air with said vaporized oil, means for initially igniting the mixture, an atomizer for atomizing a portion of said oil, means for mixing air with the atomized oil, means for heating said last named mixture by the heat of the initially ignited charge, means for regulating the temperature of said heated mixture, said last named means comprising a thermostat disposed in the path of said heated mixture, and a valve 55 controlled by the thermostat for admitting cold air directly to said heating means.

3. A vaporizing device for heavy oils comprising a casing, an oil chamber carried by the casing, means for initially heating a portion of the oil to the vaporizing

temperature, means for mixing air with said vaporized oil, means for initially igniting the mixture, an atomizer for atomizing a portion of said oil, means for mixing air with the atomized oil, means for heating 70 said last named mixture by the heat of the initially ignited charge, means for regulating the temperature of said heated mixture, said last named means comprising a thermostat disposed in the path of said heated mixture, a valve controlled by the thermostat for admitting cold air directly to said heating means, and means for adjusting the thermostat to operate at a predetermined temperature. 80

4. A vaporizer for heavy oils, comprising a burner, means for feeding heavy oil to said burner, means for vaporizing the oil, means for mixing air with the vaporized oil, means for igniting the mixture, a chamber having 85 walls adapted to be heated by said burner, means for conveying air and atomized oil into said chamber, means for conducting the heated mixture of oil and air away from said chamber, means for admitting air to cool 90 said chamber, and thermostatic means actuated by the heated mixture of oil and air for controlling said cooling means.

5. A vaporizer for heavy oils comprising a casing, a chamber for the oil, means for 95 vaporizing a portion of the oil, means for mixing air with the vaporized oil, means for igniting the mixture, means for atomizing another portion of the oil, means for mixing air with the atomized portion, means for 100 heating the atomized mixture by the heat from the ignited vaporized mixture, means for extinguishing the vaporized mixture, means for subsequently maintaining the heat supplied to the atomized mixture, said 105 last named means comprising a series of air tubes having free communication with the atomized fuel, and means for heating the air tubes.

6. A vaporizer for heavy oils comprising 110 a casing, a chamber for the oil, means for vaporizing a portion of the oil, means for mixing air with the vaporized oil, means for igniting the mixture, means for atomizing another portion of the oil, means for 115 mixing air with the atomized portion, means for heating the atomized mixture by the heat from the ignited vaporized mixture, means for extinguishing the vaporized mixture, means for subsequently maintaining the 120 heat supplied to the atomized mixture, said last named means comprising a series of air tubes having free communication with the atomized fuel, a heating flue surrounding said air tubes, and means for passing hot exhaust gases through said heating flue. 125

7. A vaporizer comprising a casing, a fuel float chamber carried by the casing at the bottom thereof, a central tube extending through said float chamber, said central tube 130

having communication with the interior of the float chamber, means within the central tube for heating oils to the vaporizing point, means at the top of the tube for mixing air with said vaporized oil, means for igniting the mixture, a series of tubes disposed above the upper end of said first named tube for receiving the heated gases, a flue surrounding said last named tube, a chamber disposed above said last named tube and having communication with said flue, and means for atomizing a portion of the fuel in said float chamber and for introducing it into the connecting means between the flue and the chamber above it.

8. A vaporizer comprising a casing, a fuel float chamber carried by the casing at the bottom thereof, a central tube extending through said float chamber, said central tube having communication with the interior of the float chamber, means within the central tube for heating oils to the vaporizing point, means at the top of the tube for mixing air with said vaporized oil, means for igniting the mixture, a series of tubes disposed above the upper end of said first named tube for receiving the heated gases, a flue surrounding said last named tube, a chamber disposed above said last named tube and having communication with said flue, means for atomizing a portion of the fuel in said float chamber and for introducing it into the connecting means between the flue and the chamber above it, and a thermostat disposed in the path of the products passing through the flue.

9. A vaporizer comprising a casing, a fuel float chamber carried by the casing at the bottom thereof, a central tube extending through said float chamber, said central tube having communication with the interior of the float chamber, means within the central tube for heating oils to the vaporizing point, means at the top of the tube for mixing air with said vaporized oil, means for igniting the mixture, a series of tubes disposed above the upper end of said first named tube for receiving the heated gases, a flue surrounding said last named tube, a chamber disposed above said last named tube and having communication with said flue, means for atomizing a portion of the fuel in said float chamber and for introducing it into the connecting means between the flue and the chamber above it, a thermostat disposed in the path of the products passing through the flue, an air inlet between the upper end of the first named tube and the lower end of the heating tube, and a valve controlled by said thermostat.

10. A vaporizer comprising a casing, a fuel float chamber carried by the casing at the bottom thereof, a central tube extending through said float chamber, said central tube having communication with the interior of the float chamber, means within the central tube for heating oils to the vaporizing point, means at the top of the tube for mixing air with said vaporized oil, means for igniting the mixture, a series of tubes disposed above the upper end of said first named tube for receiving the heated gases, a flue surrounding said last named tube, a chamber disposed above said last named tube and having communication with said flue, means for atomizing a portion of the fuel in said float chamber and for introducing it into the connecting means between the flue and the chamber above it, a thermostat disposed in the path of the products passing through the flue, an air inlet between the upper end of the first named tube and the lower end of the heating tube, a valve controlled by said thermostat, means for admitting air to the chamber above said heating tube, and means for heating said air prior to its entrance to the chamber.

11. A vaporizer comprising a casing, a fuel float chamber carried by the casing at the bottom thereof, a central tube extending through said float chamber, said central tube having communication with the interior of the float chamber, means within the central tube for heating oils to the vaporizing point, means at the top of the tube for mixing air with said vaporized oil, means for igniting the mixture, a series of tubes disposed above the upper end of said first named tube for receiving the heated gases, a flue surrounding said last named tube, a chamber disposed above said last named tube and having communication with said flue, means for atomizing a portion of the fuel in said float chamber and for introducing it into the connecting means between the flue and the chamber above it, a thermostat disposed in the path of the products passing through the flue, an air inlet between the upper end of the first named tube and the lower end of the heating tube, a valve controlled by said thermostat, means for admitting air to the chamber above said heating tube, means for heating said air prior to its entrance to the chamber, said last named means comprising flues for the exhaust gases, and air pipes extending through said flues and adapted to be heated by the heat from the exhaust gases.

CHARLES CAREY MANKER.
